UNITED STATES PATENT OFFICE.

CORNELIUS MORRISON, OF GLASGOW, KENTUCKY.

CHURN.

990,896.

Specification of Letters Patent.

Patented May 2, 1911.

Application filed March 7, 1911. Serial No. 612,770.

To all whom it may concern:

Be it known that I, CORNELIUS MORRISON, a citizen of the United States, residing at Glasgow, in the county of Barren and State 5 of Kentucky, have invented a new and useful Churn, of which the following is a specification.

This invention relates to devices employed in assisting in operating vertically movable 10 members, such as churn dashers, rod drills, and some forms of pump rods, and the like.

The primary object of said invention is to so construct a device of this character that the vertically movable member may be easily 15 and conveniently manipulated, the raising of said member being assisted by spring means, and the descent of said member being assisted by a weight.

With the above and other objects in view 20 as will appear as the description proceeds, the invention resides in the combination and arrangement of parts and in the details of construction hereinafter described and claimed, it being understood that changes in 25 the precise embodiment of invention herein disclosed can be made within the scope of what is claimed without departing from the spirit of the invention.

In the accompanying drawings forming a 30 part of this specification,—Figure 1 is a side elevation of the complete apparatus, partly in section; Fig. 2 a top plan view; Fig. 3 a detail view, partly in section, of the plunger and its supporting mechanism; 35 Fig. 4 a detail view of said plunger and supporting mechanism; Fig. 5 a detail view of the supporting bracket; and Fig. 6 a modified form of dasher.

Referring to the drawings by characters 40 of reference, 10 designates a base plate on which is positioned a cream receptacle 11. Supported by said base plate is a tubular upright 12 which receives the shank portion 13 of a bracket member 14, said bracket 45 member being formed with parallel spaced arms 15 and 16 which terminate in curved supports 17. It will be noted that said portion 13 is adjustable within the tube 12, the same being held in its adjusted position by 50 the thumb nut 18.

The plunger mechanism consists of a shaft or plunger 19 to the base portion of which is secured a dasher 20, which is connected to the shaft 19 by the weighted sleeve 20'. Ar- 55 ranged on the plunger 19 is a plurality of sleeves 21 and 22, the sleeve 21 being capable

of adjustment on said plunger, being held in adjusted position by the thumb nut 23. The sleeve 22 is provided with the enlarged bore 22' which permits the ready reciproca- 60 tion of the plunger within said sleeve. Said sleeve is provided with the trunnions 24 which terminate in heads 24'; these trunnions are, when the device is in its operative position, adapted to rest within the curved 65 support 17. A coiled spring 26 is secured at one end to the eyes 27 carried by the lower end of the sleeve 22, said coiled spring embracing the plunger, its other end being secured to the eyes 28 supported by the upper 70 end of the sleeve 21, the spring being of a gradual taper, its reduced portion being attached to the sleeve 21. It will thus be seen that with the device suspended, as shown in Fig. 1, the plunger is resiliently hung, the 75 weighted sleeve 20' tending to overcome the tendency of the spring 26, said spring normally tending to draw the sleeves 21 and 22 together. It will thus be seen that it will require but a slight movement to recipro- 80 cate the plunger through the medium of the handle 28, the downward movement of the plunger being assisted by the weighted sleeve 20', the upward movement being assisted by the spring 26, and a constant and 85 rapid reciprocation of said plunger being readily attained with very little effort on the part of the operator.

Particular attention is called to the peculiar manner of resiliently supporting the 90 plunger and to the fact that the tension of the spring member may be adjusted by means of the sleeve 21, thus increasing or diminishing the upward pull on the plunger and effectually regulating the stroke. It 95 will also be noted that the bracket member may be adjusted to accomplish this same re- sult and that when the device is not in use: or when it is desired to disassemble the parts, the trunnions may be readily removed from 100 the curved support 17.

The modification shown in Fig. 6 consists of the weighted sleeve 29 from which extends the arms 30, which arms support the dasher 31. In this way the dasher itself is 105 weighted, the sleeve 29 and the arms 30 which are formed of metal, answering the purpose of the weight 20', which is shown in the preferred form.

In the form shown in Fig. 4, the plunger 110 19 is in two sections, the lower section to which the dasher is secured extending with-

in the sleeve 21 and being held within said sleeve by set screw 21", the upper portion of said plunger being adjustably held in said sleeve by means of the set screw 23. This 5 construction permits of the ready removal of the dasher for the purpose of cleaning the same.

The many advantages of a construction of this character will be clearly apparent, 10 as it will be seen that the device forms a convenient and effective plunger operating mechanism, in which the labor of operating the plunger is reduced to a minimum.

While the device is primarily intended for 15 churning, the same is adapted for any use to which a vertically moving plunger may be applied.

What is claimed as new is:

1. In a churn operating mechanism, a base 20 plate, a receptacle arranged on said base plate, a tubular upright supported by said base plate, a bracket member, said bracket member being formed with a plurality of parallel spaced arms and a shank portion 25 extending within said tubular upright, a plunger, a weighted dasher arranged on one end of said plunger, a plurality of sleeves arranged on said plunger, one of said sleeves being secured to said plunger, trunnions 30 secured to the other sleeve and supported by the arms of said bracket, and a spring coiled around said plunger, said spring connecting said sleeves.

2. In a churn operating mechanism, a base 35 plate, a receptacle arranged on said base plate, a tubular upright supported by said plate, a bracket member, said bracket member being formed with a shank arranged to extend within said tubular member, a 40 plunger, a weighted dasher arranged on one end of said plunger, a sleeve secured to said plunger, a sleeve supported by said bracket, and a resilient connection between said sleeves.

3. In a churn operating mechanism, a 45 plunger, a weighted dasher secured to one

end of said plunger, a sleeve adjustable on said plunger, a supporting bracket, a sleeve supported by said bracket, said plunger extending through said last mentioned sleeve, 50 and a resilient connection between said sleeves.

4. In a churn operating mechanism, a plunger, a weighted dasher arranged on said plunger, a sleeve capable of adjustment 55 on said plunger, a second sleeve, said plunger extending through said second sleeve, the bore of said sleeve permitting lateral movement of said plunger, trunnions arranged on said second sleeve, a bracket member supporting said sleeve, said bracket member being adjustable, and a resilient connection between said sleeves.

5. In a churn operating mechanism, a plunger, a weighted dasher secured to said 60 plunger, a sleeve mounted on said plunger, a second sleeve, said plunger extending through an enlarged bore formed in said second sleeve, means for supporting said second sleeve, a spring coiled around said 65 plunger and secured to each of said sleeves, and means for regulating the tension of said spring.

6. In a churn operating mechanism, a movable plunger, a weighted dasher secured 70 to said plunger, a sleeve secured to said plunger, a stationary sleeve, said sleeves being resiliently connected.

7. In a churn operating mechanism, a vertically movable plunger, a weighted 80 dasher secured to said plunger, a sleeve secured to said plunger, a stationary sleeve, a coiled spring secured to each of said sleeves, the tension of said sleeve being regulated by the sleeve arranged on the plunger. 85

In testimony that I claim the foregoing as my own, I have hereto affixed my signature in the presence of two witnesses.

CORNELIUS MORRISON.
